UNITED STATES PATENT OFFICE.

NEWTON S. NOBLE, OF AKRON, OHIO, ASSIGNOR TO THE B. F. GOODRICH COMPANY, OF NEW YORK, N. Y., A CORPORATION OF NEW YORK.

UNIVERSAL-JOINT DISK.

Application filed February 7, 1921. Serial No. 442,999.

To all whom it may concern:

Be it known that I, NEWTON S. NOBLE, a citizen of the United States, residing at Akron, in the county of Summit and State of Ohio, have invented a certain new and useful Universal-Joint Disk, of which the following is a specification

This invention relates to flexible coupling members or disks for universal joints where-
10 in the disk, disposed transversely, forms a connection between two opposed coupling members at the ends of their respective shafts.

Its object is to provide a construction suit-
15 able to be simply and inexpensively formed of fibrous material such as rubberized fabric which will permit great flexibility of the joint and some relative movement of the coupling members in the lines of their axes
20 while compelling the two to rotate together without play, and thus to provide a flexible, efficient and durable joint.

Of the accompanying drawings:

Fig. 1 is an end view of a universal joint
25 with my improved disk in position therein.

Fig. 2 is a side view of the same.

Fig. 3 is a perspective view of a strip of
30 rubberized fabric showing the manner of folding it in producing my improved coupling disk.

Fig. 4 is a face view of the same.

Fig. 5 is a similar face view showing a modification.

Referring to the drawings, 10 is my coupling disk in connective position between the spider coupling members 11 of a universal joint, these spiders being secured respectively upon the adjacent ends of the driving and the driven shaft, and the arms of the
40 two spiders, on opposite sides of the disk, being secured to the latter in alternating positions by the bolts 14.

12 is a single strip of rubberized fabric, which might be ordinary square-woven
45 fabric but is preferably what is known as weak-wefted thread fabric in which the weft threads are widely-spaced and relatively weak, while the warp-threads are strong and closely spaced, to take the strain.
50 This strip I fold either in the manner illustrated in Figs. 3 and 4, or in the modified manner shown in Fig. 5, to produce an annular, equilateral, polygonal structure of several superimposed plies of fabric.
55 The outer edge of every ply of fabric is

thus a folded edge, and there are no raw edges at the outer periphery of the structure. The inner periphery of the structure has the form of a polygon similar to the outer periphery, but with its sides opposite to the angles of the latter. The stronger or warp-threads of the fabric preferably lie parallel with the side of the inner polygon in every lap, this being the direction of stress. Alternate sides of the inner polygon, 60 *ab* and *cd*, for example, if extended, would intersect approximately at an apex, *e*, of the outer polygon, the figure formed by such extensions having the form of a star and consisting of the inner polygon and a triangular extension from each of its sides. 65 Throughout the area of these triangular extensions, *b c e*, the warp of the fabric is all approximately parallel with the side of the inner polygon, *bc*, which forms the base of 70 the triangle. Thus the strong threads of the fabric lie approximately in the line of stress. Between these triangular sections there are other triangular sections, *f b e*, where there are twice as many plies of fabric 75 as in the first mentioned triangles, the warp of every ply lying in a line of stress, but alternating as to direction.

While I have shown the disk as a hexagonal figure it obviously might have a 80 greater or less number of sides.

Having folded the fabric in the manner described, I cut bolt holes, as shown at 13, Fig. 1, preferably at about the center of each of the thicker sections, *f b e*. Such sections, 85 being composed of twice as many plies of fabric as the intervening sections, afford good attachment points, while the thinner, intervening triangular sections, *b c e*, afford great flexibility, but I do not wholly limit myself to this location of the bolt holes nor to the particular style of bolted clamps here shown. I then vulcanize the disk in a suitable mold, under pressure. The bolt holes may be cut after vulcanization, but I find 100 it preferable to cut them before vulcanizing, in order that the raw fabric edges thereby produced may be bound into the rubber during vulcanization. Their tendency to ravel or fray during use is thus largely 105 reduced.

The disk is mounted between the spider coupling members 11 and secured thereto, by means of the bolts 14, which secure it alternately to the spider arms of the cou- 110

pling members 11 of the driving and of the driven shaft.

I claim:

1. A coupling disk for a universal joint, 5 said disk comprising a continuous, flat strip of rubberized fabric folded into the form of an annulus having polygonal inner and outer peripheries and having approximately twice as many thicknesses of the strip in 10 some of its parts as in substantially all of the rest of its parts.
2. A coupling disk for a universal joint, said disk comprising a continuous, flat strip of rubberized fabric folded into the form 15 of a multiple-ply annulus of substantially plane form, said strip lying in a simple succession of lengths folded forwardly about said annulus.
3. A coupling disk for a universal joint comprising a piece of rubberized fabric 20 folded to the form of a polygon, the lines of fold lying in the outer periphery of the disk, the disk being of substantially plane, polygonal form.
4. A coupling disk for a universal joint comprising a piece of rubberized fabric 25 folded to the form of a polygon, the lines of fold lying in the outer periphery of the disk, and having relatively thick sections 30 and intervening relatively thin sections.
5. A universal joint comprising a pair of

shaft spiders whose arms alternate, and a coupling disk connecting said arms and comprising a polygonal structure composed of a strip of thread fabric folded along the outer edge of the disk and having its strain-resisting threads parallel to the sides of the strip. 35

6. The method of making a coupling disk which comprises folding a piece of unvulcanized rubberized fabric to the form of a polygon, the lines of folds lying in the outer periphery of said polygon, and vulcanizing the resulting structure under pressure. 40

7. The method of making a coupling disk 45 which comprises forming a strip of rubberized fabric, folding said strip to a flat annular form with equilateral, polygonal inner and outer peripheries, the lines of fold lying in the outer periphery, cutting bolt 50 holes through the structure thus formed, and vulcanizing it in a mold under pressure.

8. The method of making a coupling disk which comprises folding a strip of unvulcanized rubberized fabric into the form of 55 a multiple-ply annulus, by a forwardly progressing series of single folds, and vulcanizing the resulting structure under pressure.

In witness whereof I have hereunto set my hand this 29 day of January, 1921.

NEWTON S. NOBLE.
